L. T. SAVAGE

WHEELED TOY

Filed July 14, 1926

Lorenzo T. Savage Inventor
By his Attorney Frank Lent

Patented Sept. 21, 1926.

Des. 71,119

UNITED STATES PATENT OFFICE.

LINNAEUS T. SAVAGE, OF EAST ORANGE, NEW JERSEY.

DESIGN FOR A WHEELED TOY.

Application filed July 14, 1926. Serial No. 18,359. Term of patent 14 years.

To all whom it may concern:

Be it known that I, LINNAEUS T. SAVAGE, a citizen of the United States of America, and resident of East Orange, county of Essex, and State of New Jersey, have invented a certain new, original, and ornamental Design for Wheeled Toy, of which the following is a specification, reference being had

to the accompanying drawing, forming part thereof.

In the drawing, the figure is a perspective view of a wheeled toy embodying the design.

I claim:—

The ornamental design for a wheeled toy, as shown.

LINNAEUS T. SAVAGE.
